WATER CONNECTION

George W. Hulshizer, Stewartsville, N. J., assignor
to Ingersoll-Rand Company, Jersey City, N. J.,
a corporation of New Jersey

Application June 26, 1937, Serial No. 150,482

6 Claims. (Cl. 121—10)

This invention relates to rock drills, and more particularly to a water connection for attaching the cleansing water supply hose to the rock drill casing.

5 One object of the invention is to maintain a fluid tight seal between the casing and a water connection swivelled in the casing.

Other objects will be in part obvious and in part pointed out hereinafter.

10 In the drawing accompanying this specification and in which similar reference numerals refer to similar parts,

15 Figure 1 is an elevation, partly broken away, of a rock drill equipped with a water connection constructed in accordance with the practice of the invention, and

Figure 2 is a transverse view taken through Figure 1 on the line 2—2.

20 Referring more particularly to the drawing, 20 designates a rock drill comprising a cylinder 21 and front and back heads 22 and 23, respectively, which constitute the casing parts of the rock drill and may be clamped together by side bolts 19.

25 The front head 22 houses a chuck mechanism 24 to accommodate a working implement 25 and an anvil block 26 for transmitting the blows of a hammer piston 27 to the working implement. The working implement is of the hollow type,

30 having a passage 28 for conveying cleansing liquid to the cutting bit (not shown). The rear end of the passage 28 accommodates the end of a water tube 29 which extends through the cylinder 20 and into a recess 30 in the back head.

35 On the rearmost extremity of the water tube 29 is a flange 31 which seats upon the bottom of the recess 30 and is held in sealing relationship therewith by a plug 32 threaded into the recess. The flange 31 and the adjacent portion

40 of the plug 32 are of smaller diameter than the recess 30 and cooperate with the wall of the recess to define an annular chamber 33 which communicates with the interior of the tube 29 through a passage or passages 34 in the plug 32.

45 The cleansing water supplied to the water tube 29 may be conveyed to the rock drill from a source of supply by a conduit of which only the terminal connection 35 connecting the conduit to the casing of the rock drill is shown. The connection 35 extends into a recess 36 in the back head, and a passage 37, also in the back head, affords communication between the inner end

50 of the recess 36 and the annular chamber 33.

In accordance with the practice of the invention the connection 35 has a reduced end por-

tion 38 extending into the passage 37, and in the bottom of the recess 36 encircling the reduced portion 38 is a packing member 39 to prevent leakage of water from the passage 37 into the recess. The packing member 39 is held in 5 position, and may be compressed, by a bushing 40 threaded into the recess to secure the connection 35 to the back head. The bushing 40 has a coniform bore of which the surface 41 serves as a seat for a similar surface 42 on the periphery of the connection 35 and cooperates therewith to form a fluid-tight joint.

10 The connection 35 is swivelled in the back head so that the conduit connected thereto may be readily oscillated from one position to another. In order to make this movement possible it is essential that the connection be capable of a slight degree of endwise movement to break the frictional engagement between the surfaces

41 and 42 and that a yielding pressure, as for 20 example that of the water and which, in the present instance, acts against a pressure surface 43 on the end of the reduced portion 38 of the connection, be employed to press the connection against the surface 41. The pressure of the 25 water, however, is often of too low a value to prevent accidental unseating of the connection, as when it is brought into contact with the work.

The connection is accordingly provided with an additional pressure surface 44, preferably located at the end of larger diameter of the coniform portion and confronting the packing member 39, although spaced with respect thereto to provide a space or chamber into which pressure fluid is supplied by a passage 45 leading from a source

30 of pressure fluid, as for example, the chamber 46 containing the throttle valve 47 which controls the admission of pressure fluid into the rock drill for actuating its percussive element.

35 The passage 45 communicates with the recess 40 36 through ports 48 in the bushing 40 and the pressure fluid thus admitted into the recess acts against the pressure surface 44 for pressing the surface 42 of the connection firmly into engagement with the surface 41 and also acts against 45 the adjacent surface of the packing member 39 to assist in compressing the packing member into sealing engagement with the reduced portion 38 of the connection.

In practice, the present invention has been 50 found to be highly desirable in devices of this character. By subjecting the connection to the pressure of the motive fluid, and which is usually of a considerable higher value than that of the water supplied to the working implement, a true

55

sealing engagement is maintained between the connection and its seat and at the same time the connection may be readily oscillated, as required, to dispose the attached conduit in a desired position.

5 I claim:

1. In a pressure fluid actuated rock drill, the combination of a casing and a conduit for liquid, a connection for conveying liquid to the conduit, sealing surfaces on the casing and the connection, a pressure surface on the connection subjected to pressure fluid for maintaining the sealing surfaces in sealing relationship with each other, and means for preventing the flow of liquid to the pressure surface.

10 2. In a pressure fluid actuated rock drill, the combination of a casing and a conduit for liquid, a connection for conveying liquid to the conduit, sealing surfaces on the casing and the connection, and a plurality of pressure surfaces on the connection, one of said pressure surfaces being subjected to the pressure of the liquid and the other pressure surface being subjected to pressure fluid for maintaining the sealing surfaces in sealing relationship with each other.

15 3. In a pressure fluid actuated rock drill, the combination of a casing and a conduit for liquid, a connection for conveying liquid to the conduit and being swivelled in the casing, frusto-conical surfaces on the connection and in the casing, a pressure surface on the connection subjected to pressure fluid to maintain the frusto-conical sur-

faces in sealing relationship with each other, and means for preventing the flow of liquid to the pressure surface.

4. A water connection comprising a casing having a passage for liquid and a channel for pressure fluid, a connection for conveying liquid to the passage and being swivelled in the casing, surfaces on the casing and the connection cooperating with each other to effect a seal, and a pressure surface on the connection subjected to pressure fluid to maintain the surfaces in sealing relationship with each other.

5. In a pressure fluid actuated rock drill, the combination of a casing and a conduit for liquid, a recess in the casing, a passage leading from the recess to the conduit, a connection swivelled in the recess and extending into the passage, a packing member encircling the connection to effect a seal between the recess and the passage, surfaces on the casing and the connection cooperating with each other to effect a seal, a pressure surface on the connection, and a passage for conveying pressure fluid into the recess against the pressure surface to maintain the said surfaces in sealing relationship with each other.

20 6. A water connection for rock drills, comprising a casing, a connection swivelled in the casing, a packing member in the casing encircling the connection, and means to retain the connection in the casing and to compress the packing member.

25 GEORGE W. HULSHIZER.
